UNITED STATES PATENT OFFICE.

HARRY A. JONES AND EDWARD W. STRUVE, OF PARSONS, KANSAS.

ADJUSTABLE-CHAIN OIL-BEARING.

1,385,135.

Specification of Letters Patent. Patented July 19, 1921.

Application filed January 3, 1919. Serial No. 269,440.

To all whom it may concern:

Be it known that we, HARRY A. JONES and EDWARD W. STRUVE, citizens of the United States, residing at Parsons, in the county of 5 Lnette and State of Kansas, have invented certain new and useful Improvements in Adjustable - Chain Oil - Bearings, of which the following is a specification.

This invention relates to lubrication, and 10 more especially to devices for carrying a lubricant to a bearing by means of a conveyer chain; and the object of the same is to effectively lubricate a shaft which revolves at a high rate of speed.

15 Another object is to provide, in proximity to said shaft bearing, a second bearing for the shaft of an idler wheel under which passes a belt leading to a pulley on the shaft first mentioned.

20 Another object is to provide means for adjusting the position of the last-named bearing so as to alter the position of the idler and therefore the tension of the belt.

These and other objects are carried out by 25 the construction set forth in the following specification and claims, and shown in the accompanying drawings, wherein—

Figure 1 is a side elevation, and

Fig. 2 is a plan view of parts showing the 30 relative position of the two bearings, while Fig. 3 is an end view of the same,

Fig. 4 is a sectional view of the main shaft bearing on the line 4—4 of Fig. 2,

Fig. 5 is a plan view of said bearing with 35 its cap removed, parts being shown in section, and

Figs. 6 and 7 are details in plan view and elevation of the adjustable bearing for the idler.

40 Referring by numerals to the said drawings, 1 designates the base of the main frame, 2 the inclined portion of its top, and 3 the flat top portion pierced with two rows of holes 4. The numeral 5 designates the

45 base of the main shaft bearing, which base is provided with holes 6 adapted to register with certain of the holes 4 so that screws or bolts 7 may be passed through them, and by this means the bearing 5 is adjustable longitudinally on the top 3 of the main frame.

50 The base 1 of said frame will itself have holes 8 through which will pass screws or bolts fastening it upon the sills or floor by which the entire framework and the parts 55 carried thereby are supported.

The main bearing (as seen in Figs. 4 and

5) consists of a lower part 10 rising from the base 5, and having out-turned flanges 11, and a cap 12 overlying the lower part and having out-turned flanges 13, the two 60 flanges being detachably connected by screws or bolts 14 passing through alined holes 15 in said flanges. Internally, the cap may be shaped to fit closely over the main shaft 16, but we have shown it as babbitted on its interior as at 17 and I reserve the widest latitude in this respect. Internally, the lower part 10 of the bearing has formed between its ends a considerable chamber 18 as best seen in Fig. 4, the ends of the chamber being 65 closed by the end walls of this part which rise high enough to underlie the shaft 16, babbetting 19 being illustrated in Fig. 4 at this point.

A chain 20 overlies the shaft and travels 75 in a channel 21 in the cap 12, the chain being endless and considerably longer than the circumference of the shaft so that its lower part hangs within the chamber 18, while its upper part rests on the top of the shaft as 80 will be obvious. Any suitable means may be provided for filling the chamber with lubricating oil and for withdrawing the same, or for withdrawing sediment which may collect therein. In Fig. 4 we have shown an 85 outlet opening closed by a plug 22, but we do not wish to be limited to these details. The end 23 of the bearing may be closed if this bearing is at the end of the shaft 16, although, as seen in Figs. 2 and 3, the end 90 may have a plug 24 which is itself tubular so as to receive the stem of an oil or grease-cup 25. Thus the plug 24 receives the end thrust of the shaft 16, and lubricant is applied to its extremity. The chain traveling 95 in oil carries the same upward over the shaft continually and into the channel 21, whence it spreads in both directions longitudinally along the shaft and over the wear faces, whether the latter are babbitted or not. Immediate access is gained to this bearing by removing the bolts or screws 14 and lifting off the cap 12. We might say that we have applied this chain form of lubricator to the shaft of a rapidly revolving saw, but we 100 do not wish to be limited in the use of the same.

In connection with this invention, we prefer also to employ a movable bearing for the shaft of an idler wheel which constitutes 110 a tightener for the belt leading to the driven pulley on said saw-shaft. As seen in Fig. 1,

the idler frame 31 rises from the inclined portion 2 of the top of the main frame, and is made up of two legs and a removable cap piece 32 held on their upper ends by screws 33. The cap piece has a nut 34 through which passes a screw 35 swivelly mounted at its lower end in an opening 36 in the top plate of a block 37 which is channeled at opposite sides as shown at 38 in Fig. 6 to travel on guides 39 extending longitudinally along the inner faces of the legs of the idler frame. Thus when this screw 35 is turned in one direction or the other, the entire block is adjusted vertically within said frame, and accordingly the bearing for the idler shaft is moved either up or down with respect to the main frame and the bearing for the saw-shaft 16. The idler shaft bearing, indicated at 40 in Fig. 1 is carried within an opening in the block 37, in which opening it is adjusted by screws 41 at its sides and 42 beneath it, all screws being threaded through the block and against the bearing so that the latter may be adjusted to take up wear and to accurately center the idler shaft, even after the block has been adjusted in its frame. It will be observed from Fig. 1 that the bearing for the main shaft 16 is inclined a little to the left, whereas the frame in which is mounted the bearing for the idler shaft is inclined a little to the right, and both rise from the main framework which is mounted on the sills or other supports. It will be observed from Fig. 2 that the idler frame 31 rises from one side of the top portion 2 of the main framework, and it will be clear to those who are familiar with erecting machinery that only those main frames adjacent the driven pulley on the main shaft will need to have the idler frames, because the idler shaft is not extended the full length of the main shaft. The latter, as suggested above, usually carries a circular saw and will be rotated at a high rate of speed. 45 The adjustment of the bearing for the idler

shaft is obviously to regulate the position of the idler wheel upon the main driving belt.

The foregoing description and the drawings have reference to what may be considered the preferred or approved form of our invention. It is to be understood that we may make such changes in construction and arrangement and combination of parts, materials, dimensions, etc., as may prove expedient and fall within the scope of the appended claims.

Having thus fully described our invention, what we claim as new and desire to secure by Letters Patent, is:—

1. The combination of a quadrangular frame having one side parallel to its base and another side at an acute angle thereto, a main bearing mounted on the first mentioned side, an idler frame mounted on the second mentioned side so as to be at right angles thereto, and an idler bearing mounted in the idler frame.

2. The combination of a main frame having part of its top flat and the remaining portion inclined, a main bearing adjustably mounted on the flat portion, an idler frame rising from and at right angles to the inclined portion of said top and composed of two legs having guides along their interior, a cap plate connecting the upper ends and containing a nut, a screw threaded in the nut, a block having channels adjustable on said guides, the lower end of the screw being swiveled in said block, and an idler shaft bearing adjustably mounted within said block, for the purpose specified.

In testimony whereof we affix our signatures in presence of two witnesses.

HARRY A. JONES.
EDWARD W. STRUVE.
